United States Patent Office

Des. 185,620
Patented June 30, 1959

185,620

PENDENT THERMOMETER

Ralph C. Wappner, Springfield, Ohio, assignor to The Ohio Thermometer Company, Springfield, Ohio, a corporation of Ohio

Application May 11, 1956, Serial No. 41,449

Term of patent 14 years

(Cl. D52—7)

Fig. 1 is front view of a pendent thermometer embodying my new design; and

Fig. 2 is a side view thereof.

I claim:

The ornamental design for a pendent thermometer, substantially as shown.
